CLAIM

The ornamental design for a gas supply plate for semiconductor manufacturing apparatus, as shown and described.

DESCRIPTION

FIG. 1 is a perspective view of a gas supply plate for semiconductor manufacturing apparatus showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is an enlarged view of the portion labeled "FIG. 7" indicated in FIG. 6;

FIG. 8 is a bottom plan view of the gas supply plate for semiconductor manufacturing apparatus of FIG. 1;

FIG. 9 is an enlarged view of the portion labeled "FIG. 9" indicated in FIG. 8; and,

FIG. 10 is a cross-sectional view, taken along a line 10-10 of FIG. 9.

The dashed-dot lines in FIGS. 6-9 represent the boundary lines of an enlarged portion of the gas supply plate for semiconductor manufacturing apparatus. The even dashed lines that define the circle in FIGS. 1, 6, 7, 8 and 9 and the even dashed lines that define the outer edge of the cross sectional view in FIG. 10 form no part of the claimed design.
